UNITED STATES PATENT OFFICE.

GEORGE MATTHEWS, OF RICHMOND, INDIANA.

SEAL FOR RECORD-BOOKS.

1,114,279.

Specification of Letters Patent.

Patented Oct. 20, 1914.

Application filed May 11, 1914. Serial No. 837,636.

To all whom it may concern:

Be it known that I, GEORGE MATTHEWS, a citizen of the United States, residing in the city of Richmond, in the county of Wayne 5 and State of Indiana, have invented new and useful Seals for Record-Books, of which the following is a full, clear, and comprehensive specification and exposition, the same being such as will enable others to 10 make and use the same with exactitude.

I am aware that record books have been made with detachable leaves, with means whereby leaves may be inserted from time to time, and having means for temporarily 15 securing the leaves in place, but this has only served as a temporary binder, but in most of the States this has not received official approval, for the reason that leaves could be removed unofficially. Therefore 20 my present invention contemplates going a step further, and after the book is complete to afford means for permanently securing the leaves and applying stamps whereby the leaves can not be removed by an unauthorized 25 person without great trouble and without showing that the same has been tampered with.

Broadly speaking my object is to provide means for sealing detachable leaf record 30 books to convert them into permanent records, the said means being neat in appearance, strong and durable in practice, easily and quickly applied, positive in operation, and which can be employed at a comparatively 35 low price, and that without altering the construction of detachable leaf binders now in use.

Other objects and particular advantages 40 of my invention will be made apparent in the course of the following description.

The preferred manner for carrying out the objects of my invention in a practical manner is shown in the accompanying drawings, in which—

Figure 1 is a perspective view of a portion of a record book and the temporary binder therefor, with which my invention is adapted to be employed. Fig. 2 is a longitudinal section of one of the sides shown in Fig. 1, taken centrally through one of the tubes, showing the construction before it has been sealed. Fig. 3 is a longitudinal section of the other one of the sides shown in Fig. 1, taken centrally 55 through the other one of the tubes, and showing the construction during the process of sealing. Fig. 4 is an end elevation of a

portion of a record book, showing the same as made into a permanent record by means of my invention. Fig. 5 is an isometrical 60 view of one of the pellets which I employ in sealing the record. And Fig. 6 is an isometrical view of a portion of the tool which may be employed for stamping the seal.

Similar indices denote like parts through 65 out the several views.

In order that the construction, the operation, and the advantages of my invention may be fully understood and better appreciated I will now take up a detailed description thereof in which I will set forth the invention as fully and as comprehensively as I may:

In the drawings numerals 1 and 2 denote the two sides of a record book, and numeral 75 3 denotes the curved back or edge, to which the sides 1 and 2 are hinged in the usual manner. Rigidly secured on the inside of the back 3 is the metal base 4 which corresponds to the curvature of and covers the 80 inner face of the back 3, to which it is rigidly connected. Formed integral with the edges of the base 4 are the tubes 5 and 6, each of which is provided at intervals with notches or spaces 7 and 7', for the purposes hereinafter set forth.

Numerals 8 and 9 denote the two rods, each adapted to fit in and operate in its respective tube 6 and 7. The said rods are slightly less in length than are the tubes, 90 and on one end of each rod is turned a hand-hold, 10 and 11 respectively, by which the rods may be operated. A channel is formed around each rod near the hand-hold, as the channel 12 shown in Fig. 2. Each of the 95 rods is provided with flattened portions forming the tongues 13 and 14 in the respective rods, the said tongues being located in alignment with the respective notches 7 and 7', as shown.

Numeral 15 designates the arms, of which there are a plurality, corresponding in number to the number of notches 7. Each of the arms 15 has an eye formed through each end thereof, each of which may be 105 slotted to form a mouth 17 whose width is such as to fit over the tongues 13 and 14.

The leaves 18 of the block are provided with apertures along their inner edges which fit over the arms 15, whereby they are held 110 together, as shown in Fig. 4. After the binder is provided with its full quota of leaves which have records printed thereon, and it is desired to seal the book into perma-

uent, but accessible, record, the procedure is then taken up as follows: Each of the rods 8 and 9 are drawn out slightly until the channels 12 are exposed beyond their tubes 5 and 6, then after ascertaining that the rods are turned in such manner that they are locked in the eyes 16, that is with the tongues 13 and 14 standing parallel with the arms 15, the outer ends of the rods are then 10 broken off at the channels 12, after which the rods are pressed into their tubes, dividing the difference between the lengths of the rods and the lengths of the tubes into equal spaces 19 and 20.

15 I now come to my invention proper: Letter A denotes a pellet of solder, or other sealing material, which may have been previously treated with some form of flux, such as acid grease. The pellets A should be of 20 less diameter than the interior of the tubes and they should be longer than the depth of the spaces 19 and 20, as shown at the left in Fig. 3.

In applying the seals the book should be 25 stood up on end, a pellet A may then be dropped into each of the two uppermost spaces 19 and 20 as the first step in the sealing process. The tubes 5 and 6 should then be heated, adjacent the pellet, to such degree as to cause the pellets to melt and fill 30 the spaces in which they are located, causing the pellets to adhere to the walls of the tubes and to the ends of the rods, when they will assume the form as shown at the right 35 in Fig. 3, thereby forming the seal A'. While the seals A' are still in a plastic condition one may take the tool B, which has a cameo letter or design on its end, as for instance the cameo letter "W", indicated by 40 C in Fig. 6, and impress it in the solder, thereby forming the intaglio letter "W", as indicated by D, thereby forming the official stamp, as shown in Fig. 4. After the said seals and stamps are completed then the 45 book may be turned end for end, after which the seals and the stamps may in like manner be applied in the opposite ends of the tubes. It is, of course, to be understood that the ends of the rods, and the interior of the tubes 50 outward from the ends of the rods are to be made bright, by abrasion or otherwise, in order that the solder will adhere thereto.

Upon the completion of the above mentioned operations it is apparent that it would 55 be impossible to remove the leaves without destroying the seals and the stamps, and even this would require a great amount of time, as the seals of both ends would have to be melted at the same time in order to 60 remove the rods.

It is evident that the above would provide a more secure record than the ordinary record books which are now officially accepted,

and it will eliminate the objections to the loose leaf record.

65

Having now fully shown and described my invention and its operation, what I claim and desire to secure by Letters Patent of the United States, is—

1. In combination with a loose leaf binder 70 having a back and a base connected to the back and tubes formed integral with the edges of the base and rods shorter than the tubes and located therein and arms having their ends pivoted around said rods and located in notches formed in the tubes and leaves carried by said arms, a sealing composition located in the ends of the tubes outward from the ends of the rods, all substantially as set forth.

2. In combination with a loose leaf binder 75 having tubes and rods shorter than the tubes and located therein and arms to retain leaves in position and having their ends connected to said rods, a sealing composition filling 80 the ends of the tubes outward from the ends of the rods to retain the rods permanently in the tubes.

3. In combination with a loose leaf binder 85 having tubes and rods shorter than the tubes located therein and arms adapted to be disposed through apertures in leaves the said rods being disposed through apertures in the end portions of the arms, a metallic sealing means, filling the ends of the tubes outward 90 from the ends of the rods and united to the interior of the tubes by heat.

4. In combination with a loose leaf binder 95 having tubes and rods shorter than the tubes and located therein, arms through the end 100 portions of which said rods are disposed, there being notches formed in the tubes to receive the end portions of said arms, fusible sealing means filling the ends of the tubes 105 outward from the ends of the rods and having identifying means impressed in the exposed surfaces thereof, substantially as set forth.

5. In combination with a loose leaf binder 110 having tubes and rods shorter than the tubes located therein, there being notches formed in the tubes to expose said rods and arms having their ends located in said notches and attached to said rods, fusible sealing means located in the ends of the tubes outward 115 from the ends of the rods and fused therewith and having identification means exposed on the surface thereof.

In testimony whereof I have hereunto subscribed my name to this specification in the 120 presence of two subscribing witnesses.

GEORGE MATTHEWS.
